UNITED STATES PATENT OFFICE.

ALONZO LINTON BAUSMAN, OF SPRINGFIELD, MASSACHUSETTS, ASSIGNOR TO NATIONAL EQUIPMENT COMPANY, OF SPRINGFIELD, MASSACHUSETTS, A CORPORATION OF MASSACHUSETTS.

CONFECTIONERY-COATING MACHINE.

Application filed February 7, 1922. Serial No. 534,791.

To all whom it may concern:

Be it known that I, ALONZO LINTON BAUSMAN, citizen of the United States, residing at Springfield, in the county of Hampden and State of Massachusetts, have invented new and useful Improvements in Confectionery-Coating Machines, of which the following is a specification.

This invention relates to improvements in confectionery coating machines and more particularly, to means for applying the bottom coating to the articles to be coated.

While the invention is capable of general application and may be used to advantage in applying a bottom coating to various articles such as cakes, biscuits, and various sorts of confections, it is especially suitable for use with frozen confections such as ice cream and other substances which have similar characteristics and tend to melt readily at the temperatures at which the confectionery coating, such as chocolate for example, is applied. The problem of coating articles of this character is complicated by the fact that the warm coating softens the frozen articles and the latter therefore lack the solid bottoms to which the coating is ordinarily held by adherence. Thus, the bottom coating cannot be sustained in the ordinary way and special provision must be made for supporting such coating at all times until it becomes congealed. Another complicating factor entering into this problem is that, due to the heat exchange between the frozen article and the warm fluid coating, the tendency is to chill and congeal the coating prematurely, when ordinary methods are used for applying the bottom coating. Ordinarily, the articles are supported during the bottom coating operation by a support or conveyer of open work construction, such as a wire belt for example. The rapid chilling of the bottom coating tends to make it cling to the wire belt and be held thereto much more firmly than it is held to the articles. Consequently, the bottom coating tends to follow the wire belt as the articles are transferred therefrom to the delivery

conveyer, with the result that the bottom coating is stripped off. In cases where this action does not occur, the bottom coatings will be found to be marred by "wire marks" due to congealing of the coating before the articles leave the wire belt, whereby the impression left by the latter in the bottom coatings cannot be smoothed out, as they usually are, because the coating does not remain in a fluid state for a sufficient length of time.

This invention has for an object to provide improved means for applying a confectionery coating to the bottom surfaces of articles and is characterized by floating the latter on a moving stream of the coating material and maintaining the support afforded by said stream up to the point where the articles are transferred to the delivery conveyer.

According to this feature of the invention, a stream of warm coating material is made to function as a supporting and conveying means for the articles and to coat the bottom surfaces of articles, particularly frozen confections, in a commercially satisfactory manner. The articles are supported on the stream completely out of contact with anything of the nature of the usual coating belt and consequently the stripping action and the marring by wire marking, described, cannot occur. Furthermore, the bottom coatings cannot sag and fall away from the articles because complete support is provided for the bottom coatings and the articles at all times until the coating congeals.

Other objects and advantages will appear in the following description and in the illustrative embodiment of the invention in the accompanying drawings, in which;

Fig. 1 is an elevational view of the bottom coating apparatus, together with article feeding and delivery conveyers usually associated therewith, the delivery conveyer frequently delivering the articles after coating to a confectionery coating machine, also exemplified conventionally in this figure;

Fig. 2 is an enlarged sectional elevational

view showing the bottom coating apparatus in full detail;

Fig. 3 is a fragmentary top plan view of a portion of Fig. 2; and

5 Fig. 4 is a fragmentary diagrammatical illustration of the bottom coating operation.

Referring to these drawings, the bottom coating apparatus is mounted in a frame A, suitably supported, as by a pedestal B, from 10 the floor. Articles to be coated are supplied to the apparatus by a feed belt 5, which is herein shown as of fabric and as arranged to travel over a table 6. The latter is supported at one end by a pedestal C 15 and at the other end from frame A, preferably in an adjustable manner, as indicated by screws 7, which permit vertical adjustment of the table and thus the delivery end of the article feeding belt. The latter is driven 20 by a roll 8, which carries a worm gear 9, driven by a worm 10, which in turn is driven by spur gears 11 from a shaft 12.

The coated articles are conveyed from the coating apparatus by a delivery conveyer 13 25 which usually, although not necessarily, also serves as the feeding conveyer for a confectionery coating machine, herein shown in conventional and fragmentary form at D. This machine may, for example, be of the 30 general type disclosed in my U. S. Letters Patent No. 1,323,948, granted December 2, 1919, which is adapted to completely coat articles fed to its conveyer E, such coating including a second bottom coating applied 35 to that applied by the bottom coating apparatus. The conveyer 13, preferably of fabric, travels over a table 14 which is supported at one end by brackets F from pedestal B and at the other end from a ledge G on the 40 casing of machine D, preferably in a manner to permit vertical adjustment as by screws 15. The table 14 is preferably provided with a jacket 14', in which a cooling medium may be circulated to cool the applied bottom 45 coatings and cause them to fully harden before the articles are delivered to the coating conveyer E of machine D. Conveyer 13 is driven by a roll 16, mounted in brackets F, which roll carries a worm gear 17. In mesh 50 with the latter is a worm 18, which is suitably connected to the shaft 11 already described. A shaft 19 is suitably connected at one end to worm 18 and at the other end to a shaft H, which is one of the driven shafts 55 of the coating machine D. The conveyer 13, at both ends of its upper lap of travel passes over relatively thin plates 20, which are adjustable longitudinally of table 14, as by screws 21. The delivery end of conveyer 5 60 is similarly arranged, the idea being to cause the conveyers to turn relatively sharp corners so that the ends can be adjusted to lie closely adjacent the next succeeding element which carries the articles. Associated with 65 conveyer 13 is a tension roll 22, which is car-

ried by levers 23 pivoted to brackets F and movable by screws 24 mounted in the brackets F.

The particular constructional details of the article feeding and discharging mechanism, although preferred, are not necessarily essential and may be varied in many particulars and still embody the invention which is concerned primarily with the bottom coating apparatus and its cooperative relation with an article feeding and discharging mechanism.

The bottom coating apparatus includes an open topped receptacle 25 (Fig. 2) which is mounted within frame A and adapted to receive a confectionery coating material, of which chocolate is a representative example. Receptacle 25 is so disposed in frame A which itself is in the form of an open topped tank, as to afford a jacket 26 in which a heating medium may be circulated to maintain the coating material at proper temperature. Disposed within tank 25, and rotatably supported at its ends in the side walls, thereof, is a roll 27, the uppermost point of which is substantially at the level of the upper stretch of conveyer 5, preferably slightly below. The delivery end of conveyer 5 is disposed closely adjacent the periphery of roll 27 as shown. At one side of roll 27 and 90 closely adjacent the feed end of conveyer 13 and with its upper portion substantially at and preferably slightly below, the level of the upper stretch of conveyer 13, is a shaft 28. The latter, as shown, is rotatably supported at its ends in the side walls of frame A although it need not necessarily rotate. Extending around roll 27 and shaft 28 is an endless belt 29, preferably of a pervious character such for example as a wire belt. 100 The roll 27 and belt 29 dip into the chocolate or other coating in tank 25 and carry it upwardly in a manner later to be described in detail.

Preferably, there is associated with belt 110 29 a tension roll 30, which is rotatably supported at its ends in the lower arms of bell crank levers 31, one of which is clearly shown in Figs. 2 and 3. Each lever is adjustably secured, as indicated, to the adjacent side wall of frame A and is mounted to swing about shaft 30, when desired. Mounted upon a hub portion 32 of each lever 31 for angular adjustment relatively thereto is a split member 33 which may be clamped to the hub portion by screws 34. These members 33 support between them a scraper 35 which engages shaft 28 in the usual way.

The roll 27, is driven by a chain 36 and suitable sprockets from the roll 16 already described. Movable with roll 16 is a gear 37, which drives a pinion 38, and movable with the latter is a gear 39 which drives a pinion 40 on shaft 28. The drive for shaft 125 130

28 is not necessarily essential, as heretofore pointed out.

The entire bottom coating apparatus may be covered as by a member 41, which is supported by resting at its ends on the side walls of frame A. Member 41 may have a transparent portion 42 through which the operation of the apparatus may be observed. The use of the member 41 provides an enclosure for the apparatus which enclosure is complete as possible and permits the desired temperature conditions to be readily maintained.

According to this invention it is desired to provide a moving stream of chocolate upon which articles to be coated, such for example, as frozen confections *a* may be floated, such articles being deposited on the stream in any desired manner but preferably by a feed belt, such as that shown at 5. For producing the stream the roll 27 and belt 29 are provided but since the latter is desirably of an open work and pervious construction, other means cooperating therewith, are necessary to maintain the stream. Such means may take the form of a plate 44 which is so supported as to underlie the upper stretch of travel of belt 29 and fill the gap between shaft 28 and roll 27, whereby to prevent the coating, at least in any substantial quantity from falling back into tank 25. As shown this plate is supported by being secured to the scraper 34 although any other suitable supporting means may be provided. While an impervious belt might be used in place of belt 29 and still embody the invention, the described arrangement is preferred because the impervious belt will not last very long and the coating will work in under the belt and clog the apparatus.

Preferably, a drip pan 46 is disposed beneath that portion of conveyer 5 which overlies receptacle 25 in order to prevent any particles of the confections falling from the conveyer from dropping into the receptacle and becoming mixed with the coating therein. This pan is particularly important when the confection is of ice cream or the like for a mixing of the latter with chocolate coating tends to thicken the coating and render it unsuitable for use until again reconditioned.

In operation, articles *a* are placed on conveyer 5 and thereby fed to the bottom apparatus. In such apparatus the roll 27 and belt 29 feed up coating from receptacle 25 and force it to travel over plate 44 forming a thick stream of coating *s* the top of which is appreciably above belt 29. This stream of coating is maintained from falling until it reaches the shaft 28 and the latter being positioned closely adjacent the feed end of conveyer 13, provides a support for the articles *a* during the bottom coating and

until they can be transferred to conveyer 13. The latter being substantially non-pervious provides a support for the coated articles until the bottom coating solidifies. The solidification of this coating is, of course, accelerated by the influence of the cooling medium circulated in jacket 14'.

The articles *a* do not come in contact with roll 27, belt 29, shaft 30 or plate 44 for a thick stream of chocolate is maintained to cover these elements and the articles are fed on to this stream and float thereon, being moved by the stream. The speed of the stream, which functions as a conveying means, is of course, controlled by the speed of roll 27 and belt 29. The articles *a*, contacting with the stream *s*, become coated on their under faces in an obvious manner but the important point is that this coating is supported and kept from prematurely congealing so that the articles are transferred to conveyer 13 while the coating is soft. The weight of the articles applied to the soft bottom coating forces it down against conveyer 13 into smooth flat form almost at the instant that the articles reach the conveyer and the bottom coatings thereafter congeal in the desired smooth form. However, in the case of frozen articles the stream of coating must be maintained up to the point of transfer to conveyer 13 for otherwise the bottom coating having nothing solid to cling to, would fall away from the articles or drop into contact with belt 29 and, by premature congealing, cling thereto with the disadvantages above set forth. By the maintenance of a thick stream of coating in a heated casing, the coating is prevented from chilling prior to the time of transfer to conveyer 13. Obviously, the articles should be moved through the bottom coating apparatus as fast as possible and the distance, which the articles have to travel therein should be made as short as possible to avoid undue softening of the articles when of a frozen character such as ice cream.

In the subsequent travel of the articles through an ordinary coating machine such as D, the congealed bottom coating serves to support the articles during their travel on the coating conveyer and affords the desired solid bottom for the bottom coating to cling to.

The invention has been disclosed herein, in an embodiment at present preferred, for illustrative purposes but the scope of the invention is defined by the appended claims rather than by the foregoing description.

Claims:

1. In combination, means for producing a moving and substantially unbroken stream of fluid coating material, feeding means to deliver articles to be coated to and upon said stream, whereby the articles are floated thereupon and coated on their under surfaces

and conveyed, and conveying means having a lap of travel starting from a point closely adjacent to the delivery end of said stream and moving in the same general direction to 5 convey the coated articles, the latter being transferred to said conveying means directly from said stream, and the conveying means having an unbroken surface to support the coated articles until their coating has hardened.

2. In combination, means for producing a moving and substantially unbroken stream of fluid coating material, feeding means to deliver articles to be coated to and upon 15 said stream, whereby the articles are floated thereupon and coated on their under surfaces and conveyed, conveying means having a lap of travel starting from a point closely adjacent to the delivery end of said 20 stream and moving in the same general direction to convey the coated articles, the latter being transferred to said conveying means directly from said stream and the conveying means having an unbroken surface 25 to support the coated articles until their coating has hardened, and means for cooling the bottom coatings during their travel on said conveying means.

3. In combination, conveying means having 30 a substantially unbroken surface to receive, support and convey articles after coating, means for producing a substantially unbroken stream of coating material moving in the same general direction as said conveying means and movable into close proximity thereto, and means to deposit articles 35 on said stream, whereby they are coated on their under surfaces during their travel on the stream and transferred directly by the 40 latter to said conveying means.

4. In combination, conveying means having 45 a substantially unbroken surface to receive, support and convey articles after coating, means for producing a substantially unbroken stream of coating material moving in the same general direction as said conveying means and movable into close proximity thereto, means to deposit articles on 50 said stream, whereby they are coated on their under surfaces during their travel on the stream and transferred directly by the latter to said conveying means, and means for cooling the coatings during the travel of the articles on said conveying means.

5. In combination, conveying means of 55 relatively impervious material for articles to be coated, a second conveying means of similar material to receive the coated articles having its receiving end spaced from the discharge end of the first named means and means for producing a moving and substantially unbroken layer of fluid coating material to fill the gap between said means and effect the bottom coating of the articles

and transfer them from one means to the other.

6. In combination, conveying means of relatively impervious material for articles to be coated, a second conveying means of similar material to receive the coated articles having its receiving end spaced from the discharge end of the first named means, and means for producing a moving and substantially unbroken layer of fluid coating material to fill the gap between said means and effect the bottom coating of the articles and transfer them from one means to the other, said second named conveying means and said stream having their article conveying laps of travel disposed in substantially a common plane.

7. In combination, conveying means of relatively impervious material for articles to be coated, a second conveying means of similar material to receive the coated articles, having its receiving end spaced from the discharge end of the first named means, and means for producing a moving and substantially unbroken layer of fluid coating material to fill the gap between said means and effect the bottom coating of the articles and transfer them from one means to the other, said first and second named conveying means and said stream having their article conveying laps of travel disposed in substantially a common plane.

8. In combination, a receptacle for coating material, an endless conveyer mounted to move through said material during a part of its travel and to carry a stream of the material along a substantially horizontal path, means for depositing articles upon said stream near one end of said path, and conveying means movable in close proximity to said stream at the other end of said path 100 to receive the articles carried by said stream, said conveying means having a substantially flat unbroken supporting surface for the coated articles.

9. In combination, a receptacle for coating material, an endless conveyer mounted to move through said material during a part of its travel and to carry a stream of the material along a substantially horizontal path, a conveyer to feed articles to said stream near one end of said path and having a part overlying said receptacle, means underlying said part to prevent drip and foreign material from the last named conveyer from entering said receptacle, and conveying means movable in close proximity to said stream at the other end of said path to receive the articles carried by said stream, said conveying means having a substantially flat unbroken supporting surface 115 for the coated articles.

10. In combination, a receptacle for coating material, an endless pervious conveyer

mounted to move through said material during a part of its travel and to carry a thick stream of the material along a substantially horizontal path, means underlying said 5 conveyer during its travel in said path to support said stream, means for depositing articles upon said stream near one end of said path, and conveying means movable in

close proximity to said stream at the other end of said path to receive the articles carried by said stream, said conveying means having a substantially flat unbroken supporting surface for the coated articles. 10

In testimony whereof I have affixed my signature.

ALONZO LINTON BAUSMAN.
